(57) **CLAIM**

The ornamental design for a front combination lamp for motor scooter, as shown and described.

DESCRIPTION

FIG. 1 is a front perspective view of a front combination lamp for motor scooter showing the present invention.

FIG. 2 is a front perspective view thereof.

FIG. 3 is a front elevation view thereof.

FIG. 4 is a right side elevation view thereof.

FIG. 5 is a left side elevation view thereof; and,

FIG. 6 is a top plan view thereof.

The portions of the front combination lamp for motor scooter shown in broken lines illustrate environmental subject matter only and form no part of the claimed design.
